UNITED STATES PATENT OFFICE.

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

RAILWAY DRAFT APPLIANCE.

1,346,538.

Specification of Letters Patent. Patented July 13, 1920.

Application filed April 16, 1920. Serial No. 374,342.

To all whom it may concern:

Be it known that I, ENOCH GEORGE, Jr., a citizen of the United States, residing at Pittsburgh, in the county of Allegheny and 5 State of Pennsylvania, have invented certain new and useful Improvements in Railway Draft Appliances; and I do hereby declare the following to be a full, clear, and exact description of the invention, such as 10 will enable others skilled in the art to which it appertains to make and use the same.

My invention relates to draft appliances for railway vehicles and particularly to a device of that character which is especially 5 designed to overcome difficulties in operating trains composed wholly or in large part of small industrial cars and open hearth charging and other mill cars over tracks having sharp vertical curves, as for example, a 10 track extending up or down an incline and then continuing along a horizontal platform. The principal object of the invention is to provide a draft appliance, suitable for the purpose indicated, which shall 15 be compact in form, strong and durable, and which shall permit the car coupler forming a part thereof to execute extended swinging movements both vertically and horizontally. In carrying out my invention I provide a 20 bracket member which is adapted to be rigidly secured to a car and pivotally connected thereto, so that it may swing vertically both above and below its normal position, a coupler supporting member which is pref- 25 erably provided at its outer end with a pocket for receiving the shank of a car coupler that is pivotally connected by means of a vertically extending pivot pin to the coupler supporting member, the latter being 30 rigidly sustained by the bracket through the instrumentality of springs which are seated upon the latter and engage the pivoted coupler supporting member on opposite sides of the pocket portion thereof. Such 35 a construction embodies the main features of my invention. Minor features of my invention, residing in certain advantageous details of construction, will hereinafter appear and be pointed out in the claims.

50 In the drawings illustrating the preferred form in which I contemplate applying the principle of my invention,

Figure 1 is a plan view of a draft appliance.

55 Fig. 2 is a side elevation of the mechanism

illustrated in Fig. 1, the head of the coupler being omitted.

Fig. 3 is a section on the line 3—3, Fig. 2.

Fig. 4 is a plan view of a modified form of draft appliance embodying the invention. 60

Fig. 5 is a side elevation of the construction illustrated in Fig. 4, the coupler head being omitted.

Fig. 6 is a detail plan view of the form of bracket member embodied in the construction 65 illustrated in Figs. 4 and 5.

In the drawings, 1 is a car coupler, 2 is a coupler supporting member to which the car coupler is attached, and 3 is a bracket member which is adapted to be rigidly connected to a car, as for example, by means of bolts passing through the openings 4 formed in the base or flange 5 of the bracket. The coupler supporting member 2 is preferably provided at its forward end with an outwardly flaring pocket 6 for receiving the shank of the coupler, said shank being preferably cylindrically curved at its rear end concentric with a vertically extended aperture which is adapted to receive a pivot pin 80 7 that also passes through corresponding vertically alined openings in the top and bottom walls of the pocket portion 6 of the coupler supporting member. If desired the head of the vertically extending pivot pin 85 7 may be flattened on opposite sides to engage upstanding lugs 8 adjacent the pivot pin opening in the upper wall of the pocket 6, the pivot pin thereby being prevented from turning when the coupler 1 swings 90 laterally with respect to the coupler supporting member 2.

The coupler supporting member is pivotally connected to the bracket 3 rearwardly of the vertically extending pivot pin 7 in 95 such manner that it is restrained from lateral movement but is capable of swinging movements both above and below its normal position. To effect this connection it is preferred to provide the bracket 3 with a plurality of spaced lugs 9 having horizontally alined pivot pin openings therein which are adapted to receive a pivot pin 10, the coupler supporting member 2 being provided with a rearwardly extending bar or 100 tongue 11 which lies between the pivot lugs 9 and is provided with a suitable opening to receive the pivot pin 10. The rear end of the tongue 11 is preferably convexly beveled, as indicated at 12, to afford clearance allow- 110

ing vertical swinging of the coupler supporting member 2, the beveled faces 12 preferably being disposed so as to limit the vertical swinging movements of the coupler 5 and its supporting member.

The bracket 3 is preferably provided at opposite sides with arms 13 which are united to the flange 5 of the bracket somewhat below the horizontally extending 10 pivot pin 10 and which slope downwardly toward the outer end of the coupler supporting member 2. The arms 13 are formed at their outer ends with upwardly opening cylindrical spring seats 14 which are respectively adapted to receive springs 15 by 15 which the coupler supporting member 2 is yieldingly sustained. The arms 13 may be reinforced by diagonally extending bracing flanges 16 which integrally connect the 20 spring cups 14 with the basal flange 5 of the bracket member, and they are also preferably united at their inner ends by a transversely extending web 17 which is recessed at its forward end as at 18 in vertical alignment with the pocket 6 of the coupler supporting member so as to leave the outer 25 ends of the arms 13 disconnected and in spaced relation.

The coupler supporting member 2 passes 30 between the springs 15 and is provided near its upper side with oppositely disposed spring seats 19 between which the pocket 6 intervenes. These spring seats, which are preferably of convex spherical form and 35 are respectively adapted to bear upon the upper ends of the springs, may be rigidly united to the pocket portion 6 and tongue 11 of the coupler supporting member 2 by horizontally extending webs or plates 20 formed integral with the coupler supporting member. It will be perceived that by 40 causing the springs 15 vertically to overlap the coupler supporting member 2 and by recessing the bracket member 3 so as to leave the arms 13 thereof spaced apart and disconnected below the pocket portion 6 of the coupler supporting member 2, as well as by 45 the downward sloping of the arms 13 of the bracket member, the device may be made compact while yet permitting the coupler 1 to execute extended swinging movements in a vertical direction.

The operation of the mechanism illustrated in Figs. 1, 2 and 3 and heretofore described will be readily understood. On 50 level track the coupler 1 is normally held in a horizontal plane by means of the springs 15 which are free to compress when the car to which the device is applied passes over a convex vertical curve. In passing over a dip such as exists at the bottom of an incline, the coupler 1 freely lifts as far as may be necessary, carrying upwardly with it the coupler supporting member 2 which turns 55 upon the pivot pin 10 by which it is secured

to the bracket 3. When level track again is reached the coupler 1 resumes its normal position in a horizontal plane due to the action of gravity.

The modified form of construction disclosed in Figs. 4, 5 and 6 is substantially like that heretofore described, except that the bracket 3^a by which the mechanism is connected to the car is provided with only a single sloping arm 13^a and the coupler supporting member 2^a is yieldingly sustained by a single spring 15^a which is seated in a spring cup 14^a at the outer end of the arm 13^a and bears upon a centrally disposed convexly curved spring seat 19^a formed on the under side of the coupler supporting member 2^a. In this form of the mechanism the car coupler, the coupler supporting member and the bracket are connected so as to be capable of the same character of 85 movements as the parts performing the same functions in the form of my invention that is illustrated in Figs. 1, 2 and 3, that is to say, the shank of the coupler 1^a, which extends into the flaring pocket 6 of the coupler supporting member 2^a, is pivotally connected to the latter by means of a vertically extending pivot pin 7^a, and the member 2^a is pivotally connected to the bracket 3^a by means of a horizontally extending 95 pivot pin 10^a which passes through perforated lugs 9^a with which the bracket is provided.

I claim:

1. In a railway draft appliance, the combination with a bracket member which is adapted to be rigidly secured to a car, of a coupler supporting member, a horizontally extending pivot pin for pivotally connecting said members so as to permit said coupler supporting member to swing vertically with respect to said bracket, yielding means interposed between said coupler supporting member and said bracket for supporting said coupler supporting member, a car coupler extending forwardly from said coupler supporting member, and a vertically extending pivot pin connecting said coupler and said coupler supporting member in advance of the pivotal connection of said coupler supporting member and bracket.

2. In a railway draft appliance, the combination with a bracket member which is adapted to be rigidly secured to a car, of a coupler supporting member, means for pivotally connecting said members to permit said coupler supporting member to have an extended swinging movement vertically with respect to said bracket member, spring means interposed between said coupler supporting member and said bracket for yieldingly supporting said coupler supporting member against downward movement with respect to said bracket member, a car coupler connected to said coupler supporting member

and extending forwardly therefrom, and means for pivotally connecting said coupler and coupler supporting member so as to permit said coupler to swing laterally.

3. In a railway draft appliance, the combination with a bracket member which is adapted to be secured to a car, of a coupler supporting member, means for pivotally connecting said members so as to permit said coupler supporting member to swing vertically both above and below its normal position, means mounted on said bracket member for yieldingly supporting said coupler supporting member against downward vertical movement, a car coupler, and means for pivotally connecting said coupler and coupler supporting member so as to permit said coupler to swing laterally in either direction with respect to said coupler supporting member.

4. In a railway draft appliance, the combination with a bracket member which is adapted to be rigidly secured to a car, of a coupler supporting member, a horizontally extending pivot pin pivotally connecting said coupler supporting member and said bracket member, a car coupler, a vertically extending pivot pin connecting said coupler and coupler supporting member, and a spring operatively interposed between said bracket member and said coupler supporting member, said bracket member being provided with a forwardly extending arm sloping downwardly from a point adjacent said horizontally extending pivot pin and forming a support for said spring.

5. In a railway draft appliance, the combination with a bracket member which is adapted to be rigidly secured to a car, of a coupler supporting member, means for pivotally connecting said members so as to permit said coupler supporting member to swing vertically but not horizontally with respect to said bracket member, means mounted on said bracket member for yieldingly supporting said coupler supporting member in advance of said means for pivotally connecting said coupler supporting member and bracket, a car coupler, and means for pivotally connecting said coupler to said coupler supporting member so that said coupler may swing laterally with respect to said coupler supporting member.

6. In a railway draft appliance, the combination with a bracket member which is adapted to be rigidly secured to a car, of a coupler supporting member, means for pivotally connecting said coupler supporting member to said bracket member, said means involving a horizontally extending pivot pin and a plurality of lugs having horizontally aligned perforations, a spring mounted on said bracket member for yieldingly supporting said coupler supporting member, a car coupler, and means for piv-

otally connecting said coupler to said coupler supporting member so as to permit said coupler to swing laterally with respect thereto, said bracket member being provided with an arm extending forwardly 70 from a point below said horizontal pivot pin and forming a support for said spring.

7. In a railway draft appliance, the combination with a bracket member provided with a plurality of arms which are spaced 75 apart and disconnected at their forward ends, of a coupler supporting member, means for pivotally connecting said coupler supporting member to said bracket member so as to allow said coupler supporting 80 member to swing vertically, springs interposed between said arms and said coupler supporting member, a car coupler, and means for pivotally connecting said coupler to said coupler supporting member so as to 85 permit said coupler to swing laterally to either side of its central position.

8. In a railway draft appliance, the combination with a bracket member provided with a plurality of arms which are spaced 90 apart and disconnected at their forward ends, of a coupler supporting member having at its forward end a pocket adapted to receive a car coupler and being provided with spring seats on opposite sides of said 95 pocket and being pivotally connected to said bracket member rearwardly of said pocket, means for pivotally connecting said coupler supporting member to said bracket member, springs respectively interposed between 100 said arms and said spring seats of the coupler supporting member, a car coupler extending into said pocket of said coupler supporting member, and means for pivotally connecting said coupler and coupler supporting member.

9. In a railway draft appliance, the combination with a bracket member, of a coupler supporting member, means for pivotally connecting said members so as to permit said coupler supporting member to swing vertically, a spring interposed between said bracket member and said coupler supporting member, a car coupler, and means for pivotally connecting said car coupler to said coupler supporting member, said coupler supporting member having a convex 115 spring seat adapted to engage said spring.

10. In a railway draft appliance, the combination with a bracket member which is 120 adapted to be rigidly connected to a car, said bracket member being provided with a plurality of spring seats and a recess between said spring seats, of a coupler supporting member having a pocket adapted to receive 125 a car coupler, means for pivotally connecting said bracket member and coupler supporting member rearwardly of said pocket, springs respectively engaging said spring seats and interposed between said bracket 130

member and said coupler supporting member, a car coupler extending into said pocket, and means for pivotally connecting said coupler and said coupler supporting member, said pocket and said recess being in vertical alinement, and said pocket and said spring seats being out of vertical alinement.

11. In a railway draft appliance, the combination with a bracket member which
5 is adapted to be rigidly secured to a car, of a coupler supporting member, means for

pivotally connecting said members so as to permit said coupler supporting member to swing vertically, a plurality of spaced springs seated upon said bracket and vertically overlapping said coupler supporting member, a car coupler, and means for pivotally connecting said coupler to said coupler supporting member so as to permit said coupler to swing laterally.

In testimony wherof I affix my signature.

ENOCH GEORGE, JR.
